COMBINED HANDLE AND PROTECTOR UNIT FOR A MEDICAL INFUSION NEEDLE

Donald R. Reiterman, Sierra Madre, Calif., assignor to
American Hospital Supply Corporation, Evanston, Ill.

Filed Apr. 16, 1970, Ser. No. 22,470

Term of patent 14 years

Int. Cl. D24—03

U.S. Cl. D83—12

FIG. 1.

FIG. 2.

FIG. 3.

FIG. 4.

FIG. 5.

FIG. 1 is a top plan view of a combined handle and protector unit for a medical infusion needle, showing my new design;

FIG. 2 is a side elevational view;

FIG. 3 is a left end elevational view of FIG. 2;

FIG. 4 is a right end elevational view of FIG. 2; and

FIG. 5 is an enlarged top perspective view.

I claim:

The ornamental design for a combined handle and protector unit for a medical infusion needle, as shown.
